W. G. COLES.

LUBRICATOR.

APPLICATION FILED DEC. 27, 1920.

1,397,037.

Patented Nov. 15, 1921.

UNITED STATES PATENT OFFICE.

WILFRED GEORGE COLES, OF MADISON, WISCONSIN.

LUBRICATOR.

1,397,037.

Specification of Letters Patent.

Patented Nov. 15, 1921.

Application filed December 27, 1920. Serial No. 433,358.

To all whom it may concern:

Be it known that I, WILFRED G. COLES, a citizen of the United States, residing at Madison, in the county of Dane and State 5 of Wisconsin, have invented certain new and useful Improvements in Lubricators, of which the following is a specification.

This invention pertains to lubricators and more directly to the force feed type wherein 10 a pump or series of pumps is employed to force the lubricant.

The invention has to do more particularly with the actuating means employed to operate the pump shaft and is designed especially for use in lubricators wherein the pump (or pumps) and the allied parts are inclosed within a reservoir or casing.

The structure is shown in the annexed drawings, wherein,—

20 Figure 1 is a vertical sectional view of a single lubricator unit or pump and the actuating mechanism, taken on the line I—I of Fig. 2;

25 Fig. 2 a transverse vertical section taken on the line II—II of Fig. 1;

Fig. 3 a detail sectional view on the line III—III of Fig. 2; and

30 Fig. 4 a perspective view of the actuating shaft, link or pitman, and the pawl carrying arm.

The main object of the invention is to provide a simple and effective mechanism for actuating the pump, the main driving shaft of which alone extends through the 35 wall of the reservoir or casing.

A further object is to so construct and position the parts that they may be readily withdrawn from the reservoir upon the removal of the cover, the various elements being connected to and sustained by the cover.

In the drawings, 1 denotes the reservoir and 2 the removable cover therefor. The oil forcing element (or elements—only one being illustrated) takes the form of a pump 45 comprising a cylinder 3, with a piston 4 working therein, the outlet or discharge pipe being indicated by 5 and the intake pipe by 6, the latter being shown as broken away but normally extending well down into the 50 reservoir. Suitable means, designated generally by 7, may be employed to control the amount of oil ejected at each stroke but

such forms no part of my invention. Piston 4 has connected thereto a yoke 8 which in turn is connected to an eccentric strap 9 mounted upon an eccentric 10 formed upon a sleeve or collar 11. Said sleeve is carried on a shaft 12 which extends therethrough and through a similar sleeve 13 to the left and through other sleeves to the right if 60 more than one pump element be present. Shaft 12 is free of any connection with the casing but forms an alining member for the various sleeves and a support for the hub 14 of a ratchet wheel 15. Hub 14 is interconnected with sleeve 11 through the medium of lugs 16 and slots 17, and the sleeve is similarly connected to the other like elements to the right where more than one pump element is present. Sleeve 13 (and 70 the corresponding element at the right of the structure—not shown) is interconnected with a stub shaft 18 mounted in a suitable bearing 19 secured in the side wall of the casing.

Secured to the under side of the cover 2 by machine screws 20 is a block or casting 21, said block forming the support for a shaft 22, the shaft carrying at its inner end a wrist pin or eccentric stud 23. A shaft 24 80 having a head 25 which is in driving engagement with shaft 22, is mounted in a bearing 26 fixed in the side wall of the casing or reservoir, motion being imparted to said shaft 24 and consequently to shaft 22 85 through a rocker arm 27. A pulley may be substituted for the arm when continuous rotary motion is desired rather than an oscillating one. A hanger 28 extends downwardly from the under side of the cover, 90 said hanger at its lower end being formed with a hub or bearing 29 through which the sleeve 13 extends. The hanger is also provided with a lateral extension (see Fig. 2) having an opening therein into which extends a flange or reduced portion 30 formed on the casting 21. The hanger thus assists in holding the block or casting 21 in position and the block likewise assists in maintaining the hanger in proper position with 100 the other parts of the apparatus. The hanger 28 is provided with an outwardly extending portion 31 formed by pressing the body thereof outwardly and upon said out-

ward extension there is secured a stud 32 which forms the pivot or fulcrum for a rocking frame 33 having formed therewith a locking pawl 34. A spring 35 coiled about the stud 32 having one end bearing upon the frame and the other upon an outwardly extending lug 36, tends to hold the pawl in locking relation with the teeth of the ratchet wheel 15.

10 Journaled upon the eccentric 23 is a pitman 37, the pitman being held in place thereon by a pin 38. The lower end of the pitman passes between the ends of a bifurcated lever 39 and a pin 40 passes through 15 said pitman and the lever, connecting the same together. The inner end of the lever 39 is provided with a hub 41 which encircles the sleeve 13 which forms the bearing for the lever. The pin 40, as will best be seen 20 upon reference to Fig. 3, is connected to the lever 39 and extends outwardly beyond the same past the ratchet wheel 15. Mounted upon said extending portion is a frame 42, similar to the frame 33, and having formed 25 therewith a pawl 43 which likewise coacts with the ratchet wheel 15. A spring 44 taking against the frame and a lug 45 extending outwardly from the lever 39, serve to force the pawl into contact with the teeth of 30 the ratchet wheel.

The operation of the structure is as follows:

When the rocker arm, as 27, is employed, an oscillating movement is imparted to the 35 shaft 22, and, as a consequence, the lever 39 is rocked back and forth through the action of the eccentric 23 and the pitman 37. The pawl 43 as the lever is raised rides over the teeth of the ratchet wheel, which at such 40 time is held against retrograde movement by the pawl 34. As the pitman begins its downward movement pawl 43 engaging the teeth of the ratchet wheel, imparts motion to the ratchet wheel and through the sleeve 45 11 will impart motion to the pump piston. Thus the pump is given a periodic impulse 50 and the oil forced to the point to be lubricated. Upon the down stroke of the piston under the next actuation of the parts, oil will be drawn into the cylinder through the intake pipe 6. When for any reason it is 55 desired to have access to the parts, all that is necessary to do is to remove the cover fasteners and bring the operative parts to that position where the shaft 22 will be free to slide upwardly away from the hub 25 and the sleeve 13 away from the head of the stub shaft 18. The cover and all of the attached parts, including the pump and the actuating 60 mechanism therefor, may then be drawn upwardly from within the reservoir and as readily replaced when desired. By having the operating shaft 24 located in the bearing at the upper part of the reservoir the chance 65 of leakage is minimized. Where the shaft

extends through the lower portion of the casing it is submerged in oil at all times except when the supply runs extremely low and leakage is liable to occur notwithstanding the employment of packing glands and 70 the like.

What is claimed is,—

1. In a lubricator, the combination of a reservoir; a cover therefor; a block secured to the under face of the cover; an operating 75 shaft extending inwardly through the upper portion of the reservoir; a second shaft interconnected with the first shaft, the second shaft having its bearing in the block; a pump likewise supported from the cover; 80 and operative connections between the shaft mounted in the block and the pump.

2. In a lubricator, the combination of a casing or reservoir; a cover therefor; a block secured to the under face of the cover; 85 a two-part operating shaft, one part being mounted in the bearing supported in the upper portion of the casing and the second part having its bearing in the block; a pump element supported from the under face of 90 the cover; a ratchet wheel; connections between said ratchet wheel and the pump for actuating the latter; and a pawl mechanism operated from the shaft supported in the block for actuating the ratchet wheel. 95

3. In a lubricator, the combination of a casing or reservoir; a cover therefor; a block secured to the under face of the cover; a shaft having its bearing in the block; a wrist pin extending outwardly from the 100 shaft; a hanger secured to the cover extending downwardly within the reservoir; a ratchet wheel; a shaft extending through the hub of the ratchet wheel; a sleeve mounted upon the shaft and passing through 105 a bearing formed in the lower portion of the hanger; a lever fulcrumed upon said sleeve; a pitman connected at one end to the lever and at its upper end to the wrist pin; a pawl carried by the lever and coacting with the 110 ratchet wheel; a second pawl mounted upon the hanger and likewise co-operating with the ratchet wheel; a pump; and suitable connections between the pump and the ratchet wheel whereby the pump is operated upon 115 the actuation of the ratchet wheel.

4. In a lubricator, the combination of a casing or reservoir; a cover therefor; a block secured to the under face of the cover; a shaft having its bearing in the block; a 120 wrist pin extending outwardly from the shaft; a hanger secured to the cover adjacent the block and extending downwardly within the reservoir, said hanger having an opening formed therein into which the side of 125 the block projects; a ratchet wheel; a shaft extending through the hub of the ratchet wheel; a sleeve mounted upon the shaft and passing through a bearing formed in the lower portion of the hanger; a lever ful- 130

crumed upon said sleeve; a pitman connected at one end to the lever and at its upper end to the wrist pin; a pawl carried by the lever and coacting with the ratchet wheel; a second pawl mounted upon the hanger and likewise coöperating with the ratchet wheel; a pump; and suitable con-

nections between the pump and the ratchet wheel whereby the pump is operated upon the actuation of the ratchet wheel. 10

In testimony whereof I have signed my name to this specification.

WILFRED GEORGE COLES.
